[57] CLAIM

The ornamental design for a scoop, as shown and described.

DESCRIPTION

FIG. 1 is a top plan view of a scoop showing our new design;

FIG. 2 is a side elevational view thereof;

FIG. 3 is a bottom plan view thereof;

FIG. 4 is an elevational view from the other side thereof;

FIG. 5 is a rear elevational view thereof;

FIG. 6 is a front elevational view thereof;

FIG. 7 is a perspective view thereof;

FIG. 8 is a bottom perspective view of an alternate embodiment, the remaining views being similar to FIGS. 1-7;

FIG. 9 is a top plan view of an alternate embodiment of FIG. 1;

FIG. 10 is a side elevational view of FIG. 9;

FIG. 11 is a bottom plan view of FIG. 9;

FIG. 12 is an elevational view from the other side of FIG. 10;

FIG. 13 is a rear elevational view of FIG. 9;

FIG. 14 is a front elevational view of FIG. 9; and,

FIG. 15 is a perspective view of FIG. 9.
